UNITED STATES PATENT OFFICE

171,172

COMBINED FLOOR LAMP AND BOOK
SUPPORT

Hilda Swede, Bronx, N. Y., assignor to Sterling
Studios Inc., New York, N. Y., a corporation of
New York

Application June 8, 1953, Serial No. 25,370

Term of patent 14 years

(Cl. D48—20)

To all whom it may concern:

Be it known that I, Hilda Swede, a citizen of the United States of America, and a resident of the Bronx, Bronx County, State of New York, have invented a new original, and ornamental Design for a Combined Floor Lamp and Book Support, of which the following is a specification, reference being had to the accompanying drawing, forming a part hereof, in which:

Fig. 1 is a side elevational view of a combined floor lamp and book support showing my new design.

Fig. 2 is a rear elevational view thereof.

I claim:

The ornamental design for a combined floor lamp and book support, as shown.

HILDA SWEDE.
